UNITED STATES PATENT OFFICE.

NILS H. CEDERQUIST, OF CHICAGO, ILLINOIS.

DESIGN FOR A TOOL.

SPECIFICATION forming part of Design No. 33,247, dated September 25, 1900.

Application filed August 6, 1900. Serial No. 26,097. Term of patent 3½ years.

To all whom it may concern:

Be it known that I, NILS H. CEDERQUIST, a citizen of the United States, residing at Chicago, in the county of Cook and State of Illinois, have invented and produced a new and original Design for Tools, of which the following is a specification, reference being had to the accompanying drawings, forming part thereof.

10 Figure 1 is a plan view of a tool, showing my new design. Fig. 2 is a view in side elevation thereof. Fig. 3 is a similar view of the opposite side of the tool, and Fig. 4 is an end view of the handle.
15 As shown in the drawings, the leading or material feature of my design consists of a hammer A and a handle B having a longitudinal slot b, provided in its end opposite the hammer with rectangular recesses b', b², 20 and b³ of different widths. Each side of the handle is formed with an inward bevel b⁴, and the slot b is divided at about its middle with a cross-piece b⁵, slightly contracted at its middle. The upper surface of the handle is provided with marks a, forming a graduate scale, 25 and the end of the handle opposite the hammer is provided with a transverse recess c.

One side of the handle is provided with marks d, some of which marks extend entirely across the handle. The opposite side thereof (see Fig. 3) is provided with marks e, forming a graduate scale. The end of the handle opposite the hammer is provided with three prongs f, f', and f², slightly separated. The prongs f and f² are inwardly beveled and have their ends slightly rounded, and the prong f' has at its end a straight-edge. The poll of the hammer is substantially rectangular in cross-section and is provided at its corners with recesses g, while the peen is beveled, as shown.

Having described my invention, what I claim as new, and desire to secure by Letters Patent, is—

The design for a tool, substantially as herein shown and described.

In testimony whereof I have signed my name to this specification in the presence of two subscribing witnesses.

NILS H. CEDERQUIST.
